UNITED STATES PATENT OFFICE.

EMIL J. PETERSON, OF ALBION, MICHIGAN, ASSIGNOR TO GALE MANUFACTURING COMPANY, OF ALBION, MICHIGAN.

MARKER FOR PLANTERS.

1,206,028.

Specification of Letters Patent. Patented Nov. 28, 1916.

Application filed July 9, 1915. Serial No. 38,957.

To all whom it may concern:

Be it known that I, EMIL J. PETERSON, citizen of the United States, residing at Albion, in the county of Calhoun and State of Michigan, have invented certain new and useful Improvements in Markers for Planters; and I do hereby declare the following to be a full, clear, and exact description of the invention, such as will enable others skilled in the art to which it appertains to make and use the same.

My invention relates to improvements in marker bars for planters and means for manipulating the same.

My device relates more particularly to that class of markers in which a single marker bar is pivotally attached to the rear end portion of the planter frame, the parts being so arranged that when the machine is traveling in one direction across the field the marker bar projects substantially at right angles to the machine frame and marks the ground for the next row, and then when the machine frame is turned at the end of the field, the marker bar is raised and turned over to operate on the opposite side of the machine.

The object of my invention is to provide mechanism for use with said marker, which will assist the operator of the planter in turning said marker bar when it is necessary to do so.

A further object of my invention is to provide a device of this class which will be simple and durable and of inexpensive construction and which may be applied to planters now in use.

With these and other objects in view, my invention consists in certain novel features of construction and combination of parts as set forth in the following specification, illustrated in the accompanying drawing, and more particularly pointed out in the appended claims.

Referring to the drawings, Figure 1 is a top plan view of a planter showing the marker bar in projected or operative position and my improvement connected therewith. Fig. 2 is a front elevation of my appliance, showing the position of the parts when the marker bar is in lowered position on the right hand side of the planter. Fig. 3 is a similar view, showing the position of the parts when the marker bar is in lowered position on the opposite side of the machine.

Fig. 4 is a similar view showing the position of the parts when the marker bar is in raised or vertical position. Fig. 5 is a vertical sectional view of my improved marker bar lifted, taken on line 5-5 of Fig. 4. Fig. 6 is a rear elevation of my appliance taken in the direction of the arrows 6-6 of Fig. 5, and having the rear half of the gear casing removed.

In the drawings A denotes the main frame of a planter which is mounted upon the supporting wheels B in the usual manner and is provided with the usual seat C for the operator. These parts are all of ordinary construction, and my attachment applies equally as well to machines of different structures. The marker bar hereinafter described is attached to the planter on the rear bar of the frame A.

The reference numeral 1 designates a bracket which is secured to the rear bar of the frame A by a single bolt 2 that passes through a thimble 2^a of said bracket. The bracket has its upper end formed in the shape of a half casing and a plate 3 is secured to said half casing by means of bolts 4 to form a complete housing. Rigidly secured to a hollow axle 5, which is loosely mounted in the housing and is retained by a bolt 5^a, is a small gear wheel 6, which meshes with a large gear wheel 7, loosely mounted on the bolt 2. The gear wheel 7 has less than double the number of teeth with which the gear 6 is provided, so that a complete revolution of the gear 7 would cause the gear 6 to move slightly less than two revolutions, for a purpose hereinafter described.

Ears 8 are rigidly provided upon the rear face of the gear 7, and pivotally secured between the ears by means of a bolt 9, is the inner end of the marker bar 10. The marker bar 10 carries at its outer end the usual disk marker 11, and a rope 12 connects the outer end with the front of the planter.

Rigidly secured to the axle 5 and on the exterior of the bracket 1, is a crank 13 which is pivotally connected to the inner end of a coil spring 14. A bracket 15 is rigidly secured to one of the side bars of the frame A and a strap 16 having a screw threaded shank 17 which passes through an aperture in said bracket 15, is secured by means of a nut 18. Notches 19 are provided in said strap and the outer end of the coil spring 110

14 may be made to engage either of said notches, thereby varying the tension of said spring 14.

5 A chain 20 connects the marker bar 10 with the seat C of the driver or operator, and is used for elevating the marker bar.

10 The operation of my device is as follows: Assuming that the marker bar is in raised or vertical position, as shown in Fig. 4, where it is held by a slight tension on the spring 14, and that the operator desires to lower the bar to operative position on the right hand side of the machine. To accomplish this he presses downwardly on the 15 marker bar, which is moving against the tension of the spring 14, until the gear 7 has moved slightly more than one-quarter of a revolution and the gear 6 has moved slightly more than one-half a revolution, 20 or until the crank 13 has passed its horizontal center at the side opposite its initial position, as shown in Fig. 2, when the operator may release the bar which obviously will be forced downward to the limit of its 25 movement by the spring 14, acting on the crank 13. It will thus be seen that after the crank 13 has passed its horizontal center on the left hand side of the bracket 1, the spring 14 through the medium of the 30 crank and gears has a tendency to force the outer end of said marker bar constantly toward the ground, thereby insuring a visible mark. When the machine has reached the end of the field and the operator wishes to 35 raise the marker, he grasps the chain 20 and draws upwardly until the outer end of the crank 13 again passes its horizontal center, when the spring 14 will raise the bar into vertical position. After turning the machine, the bar 10 is pressed down to operate 40 on the ground to the left of the machine. When the bar is pressed toward the left the crank moves first downwardly and then upwardly until it again passes its horizontal center, at which time the spring will move the bar the remainder of the distance 45 toward the ground and maintain the same in contact therewith as heretofore described.

50 From the foregoing it will be seen that I have devised an appliance which will materially assist the operator of a planter in raising the marker and bar, thereby relieving him of the strain incident hitherto to such operations and at the same time enables him to manipulate the marker bar more expeditiously. It will also be apparent that my device may be applied to machines now in use, in a short period of time 55 and at a minimum expense.

60 What I claim and desire to secure by Letters Patent is:—

65 1. An auxiliary appliance for raising the marker bar of planters, comprising an automatic raising means, and gearing provided between said automatic raising means and

said marker bar, said means exerting a downward pressure on the outer end of said bar when said bar is in lowered position.

2. An auxiliary appliance for raising the marker bar of a planter, comprising a spring 70 and gearing interposed between said spring and said marker bar for raising said marker bar.

3. In auxiliary means for manipulating the marker bar of planters, the combination 75 with a planter frame, of a marker bar, a spring having one of its ends secured to said frame, a crank to which the other end of said spring is secured, and gearing provided between said crank and said marker bar. 80

4. In auxiliary means for manipulating the marker bars of planters, the combination 85 with a planter frame, of a marker bar, a strap secured to said frame and provided with a plurality of notches, a spring having one of its ends secured in one of said notches, a crank to which the other end of the spring is secured, and gearing provided between said crank and said marker bar.

5. In auxiliary means for manipulating 90 the marker bars of planters, the combination with a planter frame, of a marker bar, a gear wheel to which the inner end of said marker bar is secured, a smaller gear meshing with the larger gear, a crank rigid with 95 said smaller gear, and a spring interposed between said crank and said frame.

6. In auxiliary means for manipulating the marker bars of planters, the combination 100 with a planter frame, of a marker bar, a large gear wheel, ears provided on said gear to which the inner end of the marker bar is pivotally connected, a smaller gear wheel meshing with said large gear, a crank rigid with said smaller gear wheel, and a 105 spring interposed between said crank and said frame.

7. The combination with a planter frame 110 and a marker bar, of a bracket secured to the rear end of said frame, gear wheels provided in said bracket, a crank rigid with one of said gear wheels and the marker bar being pivotally mounted on the other gear wheel, and a spring interposed between said crank and one of the sides of the planter 115 frame.

8. An auxiliary appliance for raising the marker bar of planters, comprising a spring and gearing interposed between said spring and marker bar for raising said marker bar, 120 said spring exerting a downward pressure on the outer end of said bar when said bar is in lowered position.

9. In a planter, the combination with the main frame, of a marker bar and auxiliary 125 means for shifting said bar from one side of the machine to the other, said auxiliary means consisting of a gear to which the marker bar is secured, a second gear meshing with said gear and having more than 130

- half the number of teeth than the same, a crank secured to said second gear, and a spring provided between said crank and a part of the frame.
- 5 10. In a planter, the combination with the main frame, of a marker bar and auxiliary means for shifting said bar from one side of the machine to the other, said auxiliary means consisting of a gear to which the 10 marker bar is secured, a second gear meshing with said first named gear, a crank secured to said second gear, and a spring provided between said crank and a part of the frame, said first named gear having less
- than double the number of teeth than the 15 second gear, whereby said spring will exert a pressure upon the outer end of said bar in one direction when the crank is below horizontal center, and a pressure in an opposite direction when the crank is above 20 the horizontal center.

In testimony whereof I affix my signature, in the presence of two witnesses.

EMIL J. PETERSON.
